[57] CLAIM

The ornamental design for a heat shield for carpet seaming irons, as shown and described.

DESCRIPTION

FIG. 1 is a perspective view of a heat shield for carpet seaming irons, showing my new design;

FIG. 2 is a top plan view, the bottom view being substantially identical thereto;

FIG. 3 is a side elevational view, the opposite side being a substantially mirror image thereof;

FIG. 4 is a front elevational view thereof;

FIG. 5 is a sectional view taken along line 5—5 of FIG. 2.

The broken line disclosure of a carpet seaming iron in FIG. 1 is for illustrative purposes only and forms no part of the claimed design.
